UNITED STATES PATENT OFFICE.

BERNARD BADANES, OF NEW YORK, N. Y.

SHOWER-BATH ATTACHMENT.

1,033,225.

Specification of Letters Patent. Patented July 23, 1912.

Application filed July 27, 1911. Serial No. 640,755.

To all whom it may concern:

Be it known that I, BERNARD BADANES, a citizen of the United States, and a resident of the borough of Bronx, in the county of New York, city and State of New York, have invented certain new and useful Improvements in Shower-Bath Attachments, of which the following is a specification.

The present invention relates to shower bath attachments, and has for its object the construction of a simple and convenient device for regulating the flow of cold and hot water.

The invention consists of the hereinafter described features of construction as pointed out in the claims.

In the drawings, the invention is embodied in a concrete and preferred form, but changes of construction may of course be made without departing from the legitimate and intended scope of the invention as defined in the claims.

In the said drawings: Figure 1 is a view in front elevation showing the shower bath attachment embodying the invention. Fig. 2 is a side elevation of the parts shown in Fig. 1, with a section through the supporting wall. Fig. 3 is a broken detail view of the valve operating means looking in a direction opposite to that shown in Fig. 2. Fig. 4 is a sectional view on the line 4—4 of Fig. 3. Fig. 5 is a sectional view through the mixing valve with the valve body in its closed position.

Similar characters of reference indicate corresponding parts in the different views.

1 indicates a supporting wall provided with the upper bracket 2 and lower bracket 3. Carried by the upper bracket 2 is the mixing valve 4, shower head 5 and curtain ring 6.

The mixing valve is composed of a valve casing 7 having the cold water inlet 8 connected to the cold water pipe 9 and the hot water inlet 10 connected to the hot water pipe 11. The valve casing further has an outlet common to both the hot and cold water and connected by means of the pipe 13 to the shower head 5.

50 In the valve casing there is a rotatable valve body 14 provided with a main passage 15 extending in a vertical direction or longitudinally of the axis of the rotatable valve body and connecting with the outlet.

55 The valve body further has two auxiliary

passages 16 and 17 spaced a distance apart circumferentially less than the distance apart of the two inlets 8 and 10 and extending from the main passage aforesaid.

Connected with the rotatable valve body 60 is an upright rotatable shaft 19 secured in position by means of the pin 20. This shaft is also seated at 21 in the lower bracket 3 and is provided with a bevel gear 22. On the lower bracket there is a stud 23 carrying the bevel gear 24 meshing with the gear 22. Mounted on the stud 23 is a handle 25 to the back of which, gear 24 is made fast, and this handle carries the pointer 26 positioned circumferentially with respect to the mixing valve so as to indicate the operative position of the same on the dial 27 which latter is also mounted on the bracket 3. 28 is a member forming stops for the operating handle 25.

When the handle 25 is operated motion will be transmitted through the shaft 19 so as to move the valve body from its closed position to the open position with the cold water inlet in communication with the outlet. The pointer 26 will now point to the word "Cold" on the dial 27. Upon further operation of the handle 25, both the hot and cold water inlets will be brought into communication with the outlet, and the pointer 26 will stand opposite the word "Warm" on the dial 27. Still further operation of the handle 25 will close the cold water and open up the hot water fully, and the pointer 26 will now be opposite the word "Hot" on 90 the dial 27.

One of the great advantages of my invention resides in the fact that by placing the mixing valve overhead at a point substantially in line with the shower-head, it is 95 not necessary to bring the water supply pipes down to a point within reach of the bather. Ordinarily the mixing valve (or valves, as the case may be), is placed right in the water supply pipes so that in order 100 to place the mixing valve (or valves) within reach of the bather it has been necessary to extend the water supply pipes in an exposed condition up past the bather. According to my invention the water supply 105 pipes lead direct to the mixing valve, extending thereto in substantially the same horizontal plane with the valve. The mixing valve is disposed overhead substantially in line with the shower-head, and the mix-

ing valve is operated and controlled by operating mechanism which through a suitable connection is extended down to a point within easy reach of the user. This arrangement practically eliminates all exposed piping; it is no longer necessary to extend the dangerous hot water pipe up on the outside of the wall past the bather; the water is led direct to the mixing valve at a point closely adjacent to the shower-head so that it is not given an opportunity to cool, and the whole device is much neater in appearance than the ordinary shower bath with its exposed and cumbersome system of piping, valves, etc.

What is claimed, is:

1. The combination of an upper wall bracket, a mixing valve and a shower head carried by said bracket, a lower wall bracket, a rotatable shaft extending from the mixing valve on the upper bracket to the lower bracket and supported by the latter, and

means for turning said shaft carried by the lower bracket.

2. In a shower bath, an overhead mixing valve, an overhead shower head connected thereto, a wall bracket supporting the mixing valve and shower head, hot and cold water supply pipes leading direct to the mixing valve and extending thereto in substantially the same horizontal plane with the mixing valve, a movable valve element to the mixing valve, and a rotatable operating rod extending from the overhead mixing valve down to a point within easy reach of the bather.

Signed at New York city, in the county of New York and State of New York this 20th day of July A. D. 1911.

BERNARD BADANES.
